UNITED STATES PATENT OFFICE.

JOSEPH D. MAHER, OF ORANGE, NEW JERSEY.

TIE HOLDER.

Application filed September 28, 1921. Serial No. 503,710.

To all whom it may concern:

Be it known that I, JOSEPH D. MAHER, a citizen of the United States, residing in Orange, in the county of Essex and State 5 of New Jersey, have invented new and useful Improvements in Tie Holders, of which the following is a specification.

This invention relates to a tie holding device whereby neck ties, particularly those of 10 the four-in-hand type may be conveniently held in a wound condition for the purpose of storing and pressing the same so that the tie will be practically smooth and free from wrinkles at all times, and ready to be used 15 whenever desired, without requiring the same to be ironed or pressed in the usual manner.

It is the object of this invention to provide a tie holder for this purpose in which 20 one or more neck ties may be held so that the same may be conveniently stowed away and also pressed and stretched while thus held so that no wrinkles are liable to form in the same while thus held, and any 25 wrinkles which were previously in the ties will be removed without resorting to the usual ironing process heretofore commonly employed.

In the accompanying drawings:

30 Figure 1 is a perspective view showing the tie holder embodying my invention, partly unfolded. Figure 2 is a similar view showing the tie holder closed and ready for stowing away or packing. Figure 3 is a transverse section, on an enlarged scale, taken on line 3—3, Fig. 1. Figure 4 is a transverse section taken on the correspondingly numbered line in Fig. 2. Figure 5 is a fragmentary transverse section taken on line 35 5—5, Fig. 1. Figure 6 is a fragmentary view of a modification of my invention.

Similar characters of reference refer to like parts throughout the several views.

The enclosing casing of my improved tie 45 holder may be variously constructed, but in the preferred form shown in the drawings, the same is preferably constructed in the form of a portfolio, which has two covers 10 and 11, the inner edges of which are provided with flanges 12 and are connected with each other in such a manner that these two 50 covers will be swung toward and from each other in the manner of a hinge, this hinge connection being effected by means of a binding cord provided with a plurality of cross loops 13 extending through the inner

edge portions of the covers and the flanges thereof and forming the hinge connection between the same.

At its outer ends, the covers 10 and 11 are 60 preferably provided with flaps 14, 14^a which are folded inwardly one relative to the other and to the covers, for the purpose of enclosing the tie supporting members which are arranged between the covers and not 65 only complete the enclosure for these tie supporting means, but also hold the same tightly in place so as to cause the holder to operate effectively for retaining the tie in shape and preventing any wrinkles from 70 being formed in the same, as well as tending to remove any wrinkles which may have been formed in the tie while the same was being worn.

These tie holding means may be organized 75 to support either one or more ties, the particular construction shown in the drawings being organized for holding two ties, it being understood, however, that this number may be varied, if desired. The means for supporting and holding each tie comprises a leaf 15 which may be constructed of card board, leather, canvas, or other comparatively stiff material, around which a tie 16 may be wound in a direction lengthwise of 80 the leaf and also lengthwise of the hinge connection between the covers of the portfolio so that the several convolutions of the tie lie flatwise against opposite flat sides of the supporting leaf and attached around the upper and lower transverse edges of this leaf, as shown at the right hand end of Fig. 1.

Each of these tie supporting leaves is connected with the portfolio by means of a retaining member which, in the preferred 95 form, consists of a comparatively long flexible outer section 17, the outer end of which is connected with one of the longitudinal edges of the respective supporting leaf. After the tie has been thus wound upon the supporting leaf, the same is rolled inwardly 100 one or more times upon the retaining member 17, so that the latter is wound around the supporting leaf and the tie thereon in a direction perpendicular, or at right angles, to the direction in which the tie is wound upon the leaf, as shown in Figs. 3 and 4, where by the several convolutions of the tie are pressed flatly against the flat surfaces of the supporting leaf and caused to remain 105 in a smooth condition, as well as causing any wrinkles in the tie to be removed there-

from by the pressure of the retaining member. For convenience in holding the supporting leaf at its inner edge by one hand while a tie is being wound thereon with the 5 other hand, the outer end portion of the retaining member is preferably provided with a hand hole 18 next to the supporting leaf. Through this hole 18 the fingers of one hand may be passed for supporting this leaf edge 10 to the adjacent longitudinal edges while the other hand is engaged in winding the tie thereon.

The main portion 17 of this retaining member may be constructed of cloth, leather, 15 or other flexible material which is not expandable and the parts are so proportioned that when the retaining member is wound fully around the tie and its supporting leaf, one of the longitudinal 20 edges of the supporting leaf will be arranged close to the inner hinged portion of the portfolio covers, so that when the portfolio is closed, the inner longitudinal edge of the respective supporting leaf will be 25 gripped by the covers of the portfolio and be held in place thereby. In order however, to ensure the engagement of the inner longitudinal edge with the hinged portion of the portfolio by a slight pressure, the inner 30 part or section 19 of each of the flexible retaining members is preferably constructed of elastic material, such as woven elastic or goring, which is preferably of such length that when the winding of the retaining 35 member around the supporting leaf and the tie, has been completed, a slight stretching of the elastic portion of the retaining member will be necessary in order to engage the inner edge of the supporting leaf with the 40 hinge portion of the portfolio, thereby causing the resilience of the elastic section of the retaining member to draw the supporting leaf at its inner edge firmly against said hinge portion of the portfolio and thereby 45 securely hold the retaining member in a tightly wound condition around the tie and supporting leaf, so that the same will operate effectively to prevent the formation of any wrinkles in the tie, as well as to remove 50 any wrinkles which may have been previously formed therein, when wearing the tie.

After the ties have been thus wound upon the supporting leaf in the one direction and 55 the retaining members have been wound around the several supporting leaves thereon in another direction, in the manner described, the portfolio may be closed, so as to confine the wound and pressed ties between the same, by turning the flaps 14, 14^a inwardly one over the other and thus closing the outer longitudinal edge of the portfolio 60 as shown in Fig. 4.

The portfolio may be secured in this 65 closed position by any suitable means, such

for instance as the cord 20 which is passed around the front edge of the portfolio and has its ends fastened together on one side of the portfolio by means of a knot or loop 21, as shown in Fig. 2, although it is to be understood that any other suitable means may be employed for thus holding the portfolio in its closed position, such for instance as a strap passed around the portfolio, or a friction press button connecting the flaps of 75 one cover with the outer side of the other cover of the portfolio.

A tie holder of this character can be produced at comparatively low cost and permits of readily stowing away ties while they are 80 not in use so as to prevent the formation of any wrinkles in the same, as well as removing previously formed wrinkles therefrom, thereby enabling ties to be worn much longer and also presenting a much neater 85 appearance.

If desired, the retaining member may consist of one or more panels 170 which are hinged to each other and to the support leaf 150 and portfolio 100, as shown in Fig. 6. 90

I claim as my invention:

1. A tie holder comprising a comparatively stiff supporting leaf upon which the tie is adapted to be wound, and a flexible retaining member attached at one end to 95 one edge of said leaf and adapted to be wound around said leaf and said tie in a direction at right angles to the direction in which the tie is wound around said leaf.

2. A tie holder comprising a comparatively stiff supporting leaf upon which the tie is adapted to be wound, and a flexible retaining member attached at one end to one edge of said leaf and adapted to be wound around said leaf and said tie in a direction at 100 right angles to the direction in which the tie is wound around said leaf, said flexible retaining member being provided with a hand hole next to said leaf.

3. A tie holder comprising a portfolio 110 consisting of two covers which are movably connected with each other, a comparatively stiff supporting leaf which is received between said covers and upon which a tie is adapted to be wound, and a retaining member connected at one end with said portfolio and at its opposite end with said supporting leaf and adapted to be wound around said leaf and tie in a direction perpendicular to the direction in which the tie is wound 115 around said leaf.

4. A tie holder comprising a portfolio 120 consisting of two covers which are movably connected with each other, a comparatively stiff supporting leaf which is received between said cover and upon which a tie is adapted to be wound, and a retaining member connected at one end with said portfolio and at its opposite end with said supporting leaf and adapted to be wound around said 125 100

leaf and tie in a direction perpendicular to the direction in which the tie is wound around said leaf, said retaining member having an elastic section capable of expansion and contraction lengthwise of the retaining member.

5. A tie holder comprising a portfolio consisting of two covers which are movably connected with each other, a comparatively stiff supporting leaf which is received be-

tween said covers and upon which a tie is adapted to be wound, a retaining member having an outer inelastic section connected with said supporting leaf and adapted to be wound around the tie and supporting leaf 15 and an inner elastic section which is connected with said portfolio at the junction of the covers of the same.

JOSEPH D. MAHER.
